CAN VACUUMIZING AND SEAMING
MACHINE

Nelson Troyer and Paul E. Pearson, Seattle,
Wash., assignors to Continental Can Company,
Inc., New York, N. Y., a corporation of New
York

Application March 18, 1932. Serial No. 599,822

2 Claims. (Cl. 113—24)

This invention relates to can vacuumizing and sealing machines and it has reference more particularly to improvements in the valve mechanism and parts associated therewith as employed in machines whereby cans are sealed under vacuo; this invention being in the nature of an improvement upon the machine of our co-pending application filed on January 13, 1931, under Serial Number 508,514.

10 It is the principal object of this invention to provide a more satisfactory and more effective sealing condition and a smoother action in the advancement of cans along the path of travel, by use of separate valves for the intaking and for 15 the delivery of cans into and from the vacuumizing chamber, as distinguished from the use of a single valve, as in the machine of the application above mentioned.

It is also an object of the invention to provide 20 a construction permitting a smoother transfer of cans within the machine from the seamer turret to the discharge valve by use of a rotating turret instead of the stationary guide plate as employed in the prior application device.

25 Other objects of the invention are to be found in the details of construction and in the combination of the various parts and in their mode of operation, as will hereinafter be described.

In accomplishing these objects, we have provided 30 the improved details of construction, the preferred forms of which are illustrated in the accompanying drawings, wherein—

Fig. 1 is a horizontal sectional view of a vacuumizing and seaming machine showing the two 35 valve construction as embodied in the present invention.

Fig. 2 is a vertical section of the machine 40 wherein the valve carrier is disposed in open position for better illustration of the valves and the driving gearing therefor.

Fig. 3 is a diagrammatic plan view of the driving gear train for the various parts of the machine.

Fig. 4 is a detail of a part of the gear train; 45 this being an elevation looking in the direction of the arrows 4—4 in Fig. 3.

Before going into the detailed description of the machine, it will be stated that in the machine described and illustrated in our previous 50 application, above mentioned, we employ a single, rotary valve in the housing of the machine by which cans were delivered into and from the vacuumizing chamber. While this single valve is quite satisfactory insofar as sealing and transmitting the cans is concerned, it has been found

that because of its size it is subject to certain deformation by reason of unequal expansion and contraction resultant to use, that is detrimental to maintaining a tightly sealed joint without a binding action. Furthermore, the size of the 60 single valve presents certain difficulties in the machining of the parts that are desirable to overcome. Also, the use of the single valve, both for the intaking and discharging of cans makes it impractical in this particular construction to 65 employ a driven turret for transferring cans from the seamer to the valve and, as a consequence, there is an undesirable unevenness in the transfer of the cans from the seamer turret to the 70 valve.

In view of the above, we have overcome the 75 difficulties and objectionable features with respect to the single valve by employing two valves; one for delivering cans into the vacuumizing machine and the other for delivering the sealed cans from the machine. This permits use of valves of such size that no sealing difficulty is 80 encountered and difficulties in machining on the valves is avoided. Also, the use of two valves makes possible a farther separation of the paths of travel of cans entering and those leaving the seamer and permits the use of a rotating transfer turret for the delivery of cans to the discharge valve and thus avoids the unevenness of 85 travel previously noted.

Referring more in detail to the drawings—

The present invention is applied to a can closing machine that is designed especially for sealing covers or top ends, onto cans which have been filled under normal atmospheric conditions, but which are to be closed in vacuo. In its present embodiment the machine comprises an airtight housing 1 forming a vacuumizing chamber 2 within which a double seaming machine, designated in its entirety by reference numeral 3, is located. In this particular instance the seamer is a two spindle machine and comprises first and second operation heads of similar construction and operation; the first operation head 4 being shown in Fig. 2. The cans 100 5 which are to be sealed are delivered in succession to the machine after they have been filled and the covers 5a loosely clinched thereon. The can feed, or delivery means, as shown best in Fig. 1, comprises a conveyer mechanism, designated in its entirety by numeral 6, from which the cans are advanced, or pushed into the pockets 7 of a rotating valve 8 by the arms 9a of a rotating turret 9. From the pockets of this valve 105 the cans are extracted upon entering the vacu- 110

umizing chamber, by the arms 10 α of a rotating extractor turret 10 which operates to advance the cans successively into the pockets 11 of an intermittently advanced seamer turret 12 whereby the cans are carried, successively and in proper timing to the seamer heads which operate to double seam the covers onto the can bodies.

The turret 12, by reason of its intermittent advance movements, delivers the cans after the covers have been seamed thereon, to a transfer turret 13 having arms 13 α operable to advance the cans without change of speed of travel, into the pockets 14 α of a rotating discharge valve 14 whereby the cans are delivered from the vacuum chamber, whereupon they are extracted from the valve pockets by the action of the arms 15 α of a revolving extractor turret 15 with which suitable conveying mechanism as at 16, is associated to carry the cans from the machine.

The housing 1 which contains the double seamer is provided with suitable side openings through which access may be had to the internal mechanism for repair, adjustment or replacement. This housing is mounted securely upon a supporting housing 18 which contains the gearing and other transmission mechanism for driving the machine, and this housing 18, in turn, is supported upon a bed plate or base 19 which is extended sufficiently at one side to serve as a support for the valve carrier hinge shaft and driving gears presently described.

The main drive shaft 20 of the machine extends transversely and horizontally through the base housing 18. At one end of the shaft is a driving pulley wheel 23 adapted to be operatively connected with or disconnected from the shaft by clutch mechanism of suitable character under manual control or automatic control; this mechanism not herein being illustrated as it forms no pertinent part of the present invention.

Keyed onto the main driving shaft 20 as seen in Fig. 3, is a gear 25 meshing with and driving a gear 26 keyed on a shaft 27 supported parallel with and below shaft 20. This shaft 27 is formed with a worm gear 28, see Fig. 2, which meshes with a gear 29 that is disposed within a housing 30 and which is keyed on a shaft 31 extended from the housing; this latter shaft having its outer end rotatably mounted in a bearing 32 fixed on the outer end of the bed plate 19.

The turret 12 of the seamer is intermittently advanced in proper timing with the valve mechanism and transfer turrets by a geared connection with the shaft 27 consisting of a gear wheel 33 on shaft 27 meshing with and driving a gear 34 on a cross shaft 34 α , this latter shaft being connected to the turret spindle 12 α , see Fig. 2, by an intermittent gear drive designated in its entirety at 34 β .

The two valves 8 and 14, whereby the cans are delivered into and from the vacuumizing chamber are contained rotatably within a valve housing 35. This is bolted or otherwise suitably fastened upon a base frame 36 within which valve supporting spindles 37 and 38 are rotatably mounted. The valves 8 and 14 are securely fixed upon the upper ends of these spindles and are rotated thereby.

As seen best in Fig. 2, the spindles 37 and 38 are revoluble in bearings 37' and 38' at their lower ends and in taper bearings 37 α and 38 α at their upper ends. At their upper ends the valves 75 8 and 14 have journal extensions 8 α and 14 α ,

respectively, revolubly contained in bearings 8' and 14' carried in the cover plates fixed on the valve housing 35.

The valve housing 35 and base housing 36 are provided with lateral portions, formed with vertically aligned bearings 39—39' disposed between journal bearings 40—40' fixed to the vacuum chamber housing, and also in alignment with a bearing socket 41 formed in the bed plate 19. These aligned bearings contain a vertical shaft 42 which serves as a supporting hinge pin for the valve housing and base and about which these parts may swing to and from closed relation with respect to the housing of the vacuum chamber. This swinging movement of the valve housing is best illustrated in Fig. 1 wherein the housing is shown in closed position in full lines and in open position in dotted lines; the feed conveyor and turrets being carried therewith in its swinging movement.

To provide for a tightly sealed joint between the valve housing and the vacuum chamber, when the machine is closed, the chamber housing is formed at one side with an inwardly rounded wall seat 45 provided with an opening 46 of considerable extent. The valve housing 35 is correspondingly rounded outwardly to snugly fit against the seat 45 and it has an opening 47 adapted to register with the opening 46 when the valve is closed. A packing strip 48 of suitable material is inset in a groove in the valve housing about the opening so, as to preclude any possible leakage of air into the chamber through this joint. A locking hasp is pivotally attached, as at 50, to the chamber housing to engage with a bracket 51 on the valve housing to hold the latter closed, but is disengageable therefrom when it is desired to open the housing.

The valve housing is formed with two separate passages providing communication therethrough between the inside and outside of the vacuumizing chamber; one being the can inlet passage and the other the outlet. The valve 8 is revolubly fitted within the inlet passage and the valve 14 likewise is revolubly fitted within the outlet. Each valve is in the form of a downwardly tapered cylinder, formed with three equally spaced pockets in its side walls within which the cans are received and conveyed. These valves are rotated in synchronism through the medium of their supporting spindles 37 and 38 which, at their lower ends have gear wheels 53 and 54 keyed thereon, respectively and these gears are connected through the medium of an idler gear 55 carried on a supporting shaft 56 fixed on the housing 36. The gear wheel 54 is operatively connected to the valve driving shaft 31 through the medium of a gear train as shown in Fig. 3, including an idler gear 61, a driven gear 58 that is formed on the upper end of a sleeve 59 rotatable about the lower end of the hinge shaft 42, a bevel gear 60 keyed on the lower end of the sleeve, a bevel gear 61 α that is formed on and fixed to another sleeve 62 revoluble about shaft 31 within the bearing 32; this latter sleeve being normally 125 operatively connected to the shaft 31 through the medium of an automatically releasing clutch mechanism, fully described in our previous application, and herein indicated in its entirety by numeral 63. This clutch operates incidental to 130 abnormal strain on the working parts of the valve mechanism to effect an automatic disruption of the driving mechanism of the machine.

With the valve carrier in closed position as in Fig. 1 the machine in operation delivers cans, in 150

proper timing and spacing, into the pockets of valve 8 from which they are extracted upon entering the chamber by the turret 10 and are transferred to the seamer turret. From the 5 seamer the cans are finally transferred back to valve 14 by the turret 13 and the valve carries them to the outside of the chamber whereupon they are extracted from the valve and transferred to the conveyer 16 by the turret 15.

10 Referring again to the devices associated with the valve mechanism for feeding cans into and from the chamber, it will be observed that the transfer turret 10 is mounted upon the upper end of a vertical shaft 65 driven by a gear wheel 15 66 at its lower end operating in mesh with the driving gear 54 of valve spindle 38. Likewise, the extractor turret 15 is mounted upon a vertical shaft 68 revoluble in the housing 36 and having a driving gear 69 at its lower end meshing with the 20 driving gear wheel 53 of the valve spindle 37. The transfer turret 13 is fixed on the upper end of a vertical shaft 70 mounted in the housing 36 and provided at its lower end with a driving gear wheel 71 operatively connected through idler 25 gears 72 and 73 with the gear wheel 53; all gears mentioned being so proportioned that all of the various parts will operate in proper timing to cooperatively carry out their separate functions.

The conveyer turret 9 is driven by a geared 30 connection with the gear wheel 58. As seen in Fig. 3 this turret is carried by a vertical shaft 75 equipped with a driving gear 76 at its lower end meshing with gear 58. The feed conveyer mechanism 6 is driven by gearing connected with the gear 53. This consists of a bevel gear 78 fixed on the lower end of the shaft 68 to drive a bevel gear 79 with which a sprocket wheel 80 is formed as seen in Fig. 4. The conveyer 16 consists of a sprocket chain belt that extends about the 40 sprocket wheel 80 and a sprocket 82 on the outer end of the feed mechanism drive shaft 83; the latter as seen in Fig. 3, extending at a right angle to the direction of the conveyer mechanism 6 and having sprockets 84 and 85 at its inner end 45 over which chain belts 86 and 87 operate lengthwise within the feed conveyer guideway 88 to carry the cans 5 to the turret 9. A timing screw 90 is located along one side of the guideway 88 to space and time the cans in their delivery to the turret 9. This screw is driven by a geared 50 connection with the chain belt 87 as designated at 91.

The double seamer 3 contained within the vacuum chamber is also driven by a connection with the main shaft 20, as shown in Figs. 1 and 2, wherein 95 designates the seamer drive shaft and 96 as bevel gear keyed thereon and meshing with a bevel gear 97 fixed on the shaft 20. The construction and operation of the seamer will not 55 be described except to say that the turret 12 operates to intermittently advance the cans received in its pockets 11 in succession to the seaming heads which operate thereon to close the seam. The turret then delivers the cans to position for advancement by the turret 13 into the 60

pockets of the valve 14 which, in turn, delivers the cans to the exterior of the chamber where they are extracted and delivered onto conveyer 16 by the turret 15.

With this construction all of the devices carried on the valve supporting base are kept in proper timing regardless of opening or closing of the machine because of the fact that all gears in the driving chain are always in mesh and all are driven through the gear wheel 58 on the hinge shaft 42. This permits the valve support to be swung to open position without disengagement of gears. It also permits the valves and conveyers to be driven while the valve is open. The valve then may be closed without requiring any re-setting or adjustment.

This provision of two valves gives more space between the paths of the can entering and leaving the vacuum chamber and this makes possible the insertion of the delivery turret 13 for effecting a smoother action. Also, the reduction in size of the valves makes possible a certain accuracy in machining their surfaces that preclude leakage, and avoids the possibility of distortion or warping of the valve under different temperature conditions.

Having thus described our invention what we claim as new therein and desire to secure by Letters Patent is—

1. In a machine for closing cans in vacuo, a 105 seaming machine, a housing forming a vacuum chamber enclosing the said machine and having an opening, a hinge shaft supported from the housing, a valve housing supported by the hinge shaft to swing from open position to closed position over the housing opening in an air sealed joint, inlet and discharge passages in the said valve housing providing communication between the interior and exterior of the chamber, rotary pocketed valves operable in said passages for the 110 delivery of cans into and from the chamber through said opening; each of said valves having a driving spindle, driving gears for the spindles, a driven gear coaxial of the hinge shaft and driving gears for the said valves in a train driven 115 by said driven gear.

2. In a machine of the character described, a can closing mechanism, a housing enclosing said mechanism having an opening, a closure section hingedly attached to the housing to swing from 120 open position to closed position at which it has a sealed connection with the housing about the housing opening; said section having two separate openings therein, individual valve devices operable in each opening of said section, means 125 for rotating the valve devices for delivery of cans into and from the housing, and other devices mounted by said section and rotating in synchronism with the valve devices to deliver cans from one valve device to the closing machine and from the closing machine to the other valve device for delivery from the housing.

NELSON TROYER.
